UNITED STATES PATENT OFFICE.

AUGUST HOBA, OF SEATTLE, WASHINGTON.

CARTON-FOLDING MACHINE.

Application filed November 1, 1927. Serial No. 230,265.

My invention relates to machines for folding paper cartons of the type having overlapping end flaps provided with complementary interlocking slot and tongue.

5 The object of my invention is to provide a machine which will reliably fold such cartons at a reasonably rapid rate, leaving them in position for filling, and one which is cheap to build and operate, thus especially 10 adapting it for places where the number of cartons to be filled will not justify a highly elaborate and expensive machine.

My invention consists of a machine which is operable by hand, both as to placing the 15 carton blanks and actuating the machine. It is, of course, evident that power actuating connections may be applied thereto, and also that the application of automatic feeding means for the blanks is not forbidden.

20 My invention consists of certain novel constructions and combinations of parts which will be hereinafter described. The novel parts upon which I claim patent protection will be particularly pointed out in 25 the claims.

In the accompanying drawings I have shown a construction in which my invention is embodied, the same being chosen as adapted to illustrate the principles of my 30 invention without, however, implying that my invention is limited solely to the construction illustrated.

Figure 1 is a front elevation of the machine with parts thereof at the left-hand 35 portion of the figure in section.

Figure 2 is a sectional elevation taken on a plane extending from front to rear just forward of the center of its width.

Figure 3 is a plan view of the folding 40 means, showing these in open position.

Figure 4 is a transverse section of the folding means in the position occupied when the folding operation has been completed.

Figure 5 is a longitudinal section through 45 one of the end flap folding wings, this being on the line 5—5 of Figure 3.

Figures 6 and 7 are sectional elevations, viewed from the front, showing the folding mechanisms in consecutive positions, Figure 7 being that occupied at the completion 50 of the fold.

Figures 8, 9 and 10 are perspectives showing successive steps in the folding operation and the positions occupied by the folding members during such operation.

The type of carton upon which my in-

vention is designed to operate, is that which has end flaps folding together to constitute the end walls and in which two flaps extending from opposite side sections are provided, respectively with complementary slot and interlocking tongue entering said slot.

In constructing my machine any suitable type of supporting frame may be employed. In general it will have a table or working 65 surface as 1 which has mounted thereon or incorporated therein the folding members.

In this table is located a recessed die or carton-receiving and folding member 10, of a size corresponding with that of the folded 70 carton. In depth it may be a minor portion only of that of the folded carton. Along the front side of this recess the table surface is raised, forming a ledge or platform 11 upon which is placed the front side section 75 of the carton when it is positioned for folding.

Mounted for vertically reciprocating movement above this die or recess 1, and adapted to enter said recess when depressed, 80 is a folding plunger 2. This has a lower face or a horizontal area corresponding substantially with that of the folded carton. The manner of mounting this plunger illustrated employs two rods 20 fixed with relation to the plunger and sliding in guides 13 85 carried by a member 12 of the frame.

The vertical movement of the plunger may be secured by any suitable means. That illustrated consists of a lever 21 pivoted at 22 and having a slot 23 receiving a pin 28 carried by the plunger guide rods 20, and a rod 24 which connects the swinging end of lever 21, with an operating treadle 25 which is pivoted at 27. A spring, as 95 26, may be employed to raise these parts after their depression. Also, a counterweight 29 or its equivalent may be mounted upon an extension of the lever 21.

At each end of the forming recess or die 100 10 is an abutment, finger 3 which first functions in the folding cycle to start the upward folding of those end flaps 44 which are connected with the end edges of the bottom section 4 of the carton, as the plunger 105 2 starts pressing the carton blank into the die. It has another function at a later point in the cycle.

Hinged at either end of the forming die 10 is a folding wing 5. The purpose of 110 these is to fold over the end flaps 46 and 48 which are connected with respectively the

rear side section 41 and the front side section 40 of the carton. The hinges 50 of these wings have their axes inclined somewhat to the plane of the end of the carton, 5 as is clearly illustrated by the inclined position of the wings in Figures 3 and 8.

The means illustrated for actuating these wings are as follows: To the back of each wing is pivoted a rod 6 which is pivoted to 10 a lever 60, the latter being pivoted at 61 and upon its other end preferably provided with roller 62 designed to reduce friction. These ends of levers 60 are engaged and depressed by engagement therewith of a head 63 carried by a vertically reciprocating rod 64 15 slidable in a guide 67. The upper end of rod 64 has a head 65 which is engaged, with the carton intervening, by the plunger 2 when it is forced into the die 10 to thereby 20 cause the levers 60 to swing and these to swing up the folding wings 5. A spring 66 raises the rod 64. Additional springs may be desirable to cause prompt return swing of the folding wings.

25 At the rear edge of the die 10 is a folding plate 7, pivoted at 70 to have an end 71 projecting somewhat into the outline or area of the die. At each side of the arm or plate 7 and at the rear edge of the forming die or recess 10, are elevations 73 extending slightly above the level of the working surface of the table 1, these acting to start the upward swing of the rear section 41 of the carton and of the parts connected therewith, 30 before the upward swing of plate 7 begins. When the latter swings upwardly, its forwardly curved tips 72 contact with the end flaps 45 to swing these and flaps 46 forwardly to where they are engaged by the 35 folding wings 5 to complete the fold and the tucking of the tongue 47 into place. The tongue 47 has a slight cut 49' in its forward edge which forms a locking engagement with the walls of slot 49 to prevent withdrawal of the tongue.

40 The active face of folding wings 5 are of peculiar shape. That portion of the front end section lying forwardly of the rear end of the slot 49 in end flap 48, is cut away or recessed to a point outwardly of its hinge which will permit the ledge 51 to extend over the upper end of the abutment fingers 3. The rear end section 52 of the acting face of wing 5 slopes towards its back face 45 which together with the angular position of the pivot axis 50 causes somewhat slower folding action of the flap 46 than of flap 48. In consequence flap 48 is folded up first so as to lie inside of flap 46.

46 As the plunger 2 descends the end flaps 48 are positioned so that abutment fingers 3 slightly press or hold outwardly that portion of flaps 48 just below slots 49 while the edge or rib 51 of wing 5 forces that part 55 of the same flaps above said slots inwardly,

thereby opening the slots so that as flap 46 is swung forwardly, the tongues 47 will be caused to enter the slots to a point where they lock the two flaps together. In doing this the tongues slide over and are guided by the surfaces 52 of the rear section of folding wings 5. The carton is left folded, but with the top open for reception of its contents.

If it is desired to provide the carton with 75 a lining paper, this is placed with the carton and is folded therewith. Guide stops of any suitable character may be provided to accurately position the carton for folding. Such stops 8 are shown in Figure 3.

80 What I claim as my invention is:

1. In a machine for folding cartons of the type having end flaps of which one has a slit and the other a locking tongue adapted to enter the said slit, a reciprocating plunger 85 about which the carton sides are folded, a stationary finger at each end of the carton adapted to engage the inner face of the end flap which contains the tongue-receiving slit at a point just below said slit to hold the same outwardly, folding wings engaging the outer faces of the end flaps, and means for swinging them upwardly and inwardly to fold the end flaps, means for similarly swinging the back side section of the carton 90 and its attached end tuck flaps, the end flap folding wings having an inward projection positioned to engage the slotted end flaps just above the slits therein to act in conjunction with the above named fingers to open 95 said slits for the reception of the locking tongues.

100 2. A carton folding machine having means for folding up the front side flaps and their attached slotted end flaps, means for folding up the back side flaps and its attached tongue carrying end flaps, fingers engaging the inside faces of the said slotted end flaps just below their slits, and folding wings movable to fold down said end flaps and having projections engaging the slotted end flaps just above their slits to thereby 105 open said slits to receive the locking tongues of the other end flaps.

110 3. A carton folding machine comprising a table section having a carton receiving recess forming a folding die, the forward side edge thereof being highest to first fold the front side wall of the carton, wings 115 hinged at the ends of said recess to swing upwardly and inwardly to fold the end flaps, a plunger guided to reciprocate, vertically to engage and depress the carton bottom and to also thereby fold the front and rear sides of the carton, a plunger mounted for vertical movement beneath the carton bottom and connected with said wings to actuate them.

120 4. A carton folding machine comprising a recessed die of a size corresponding with the folded carton, a carton folding plunger 125

movable into said die and in co-operation therewith to fold the side and end walls of the carton, a vertically movable plunger projecting from below into said die, means acting to normally hold said latter plunger raised, folding wings hinged at the ends of the forming die and lever mechanisms actuated by the depression of the last named plunger to actuate said end folding wings.

5. In a carton folding machine, means for folding up the back and front side sections of the carton, and those end sections of the carton which are directly attached to the bottom section, folding wings operable in a swinging manner to engage the interlocking end flaps which are directly connected with the end edges of the front and back sections of the carton to fold said flaps into place, said wings being constructed and operated to swing into place that one of said flaps which contains the locking slot in advance of that one which contains the locking tongue.

6. In a carton folding machine, means for folding up the back and front side sections of the carton, and those end sections which are directly attached to the bottom section, folding wings hinged at each end of the carton upon axes which are somewhat inclined to the plane of the folded carton end, whereby when swung upwardly one of the interlocking end flaps will be swung into place slightly in advance of the other.

7. In a carton folding machine, means for folding up the back and front side sections of the carton, and those end sections which are directly attached to the bottom section, folding wings hinged at each end of the carton upon axes which are somewhat inclined to the plane of the folded carton end, in a direction which folds into place that end flap which contains the interlocking slot slightly in advance of the folding into place of the flap which contains the interlocking tongue.

8. In a machine for folding cartons having interlocking slot and tongue in respective end flaps, an abutment finger engaging

the inner face of that flap which contains the slot at a point just below the slot, a folding wing hinged to swing upwardly to engage said interlocking end flaps and swing them into the plane of the carton end, said wing having a surface engaging the outer face of that flap containing the slot along a line extending just above the slot and being relatively recessed below said slot, whereby the same co-operates with the abutment finger to open said slot for the reception of the locking tongue.

9. In a machine for folding cartons having interlocking end flaps folding, wings hinged at the ends of the carton to fold over the interlocking end flaps, the folding faces of said wings when the wing is swung up being inclined away from the plane of the carton end opposite the rear half of the carton end, and in the forward half being recessed back from the level of the slot downwardly, an abutment finger engaging the inner face of the end flap containing the slot and positioned to lie within said recess, and means for swinging the interlocking end flap containing the tongue after the slot-containing flap has been folded into position.

10. In a machine for folding cartons, a die member into which the carton is folded, a reciprocating plunger adapted to enter said die to fold the carton, folding wings at the end of the die pivoted to swing upwardly to fold the end flaps, a vertically movable plunger extending into the die recess from below, two levers pivoted beneath the die and having ends engaged by said last named plunger to be swung thereby, the plunger engaged ends of said levers being of a length to permit the plunger to pass between them when they have reached a predetermined angle of swing, and links connecting the other ends of said levers with the folding wings to thereby swing them.

Signed at Seattle, Washington, this 26th day of October, 1927.

AUGUST HOBA.
